UNITED STATES PATENT OFFICE.

ALBERT L. GRAY, OF ST. LOUIS, MISSOURI, ASSIGNOR TO THE A. L. GRAY SYRINGE COMPANY, OF MISSOURI.

DESIGN FOR A SYRINGE.

SPECIFICATION forming part of Design No. 33,684, dated December 11, 1900.

Application filed October 22, 1900. Serial No. 33,977. Term of patent 14 years.

To all whom it may concern:

Be it known that I, ALBERT L. GRAY, a citizen of the United States, residing in the city of St. Louis, in the State of Missouri, have invented and produced a new and original Design for Syringes, of which the following is a specification, reference being had to the accompanying drawings, forming part thereof.

Figure 1 is a plan view of the syringe, showing my design. Fig. 2 is a longitudinal sectional view.

As shown in the drawings, the leading or material features of my design consist of the shape of the bulb, the relatively large size of the tubular boss thereon, and the relative thickness of the tube and the arrangement of the perforations therein. The shape of the bulb is spherical, with a tubular neck. The

diameter of the tube is less than that of the boss, and the wall of the tube is of considerable thickness relative to the bore thereof. The end of the tube is rounded and imperforate, the perforations being arranged in series lengthwise of the tube.

What I claim is—

The design for a syringe, as herein shown and described.

In testimony whereof I have signed my name to this specification, in the presence of two subscribing witnesses, this 19th day of October, 1900, at the city of St. Louis, Missouri.

ALBERT L. GRAY.
